UNITED STATES PATENT OFFICE.

EDWIN A. JACKSON, OF NEW YORK, N. Y.

DESIGN FOR A FIRE-PLACE FRONT.

SPECIFICATION forming part of Design No. 16,136, dated June 23, 1885.

Application filed February 24, 1885. Term of patent 3½ years.

To all whom it may concern:

Be it known that I, EDWIN A. JACKSON, a citizen of the United States, residing at New York, in the county of New York and State 5 of New York, have invented a certain new and original Design for Fire-Place Fronts; and I do declare the following to be a full, clear, and exact description of the invention, such as will enable others skilled in the art to which 10 it appertains to make and use the same, reference being had to the accompanying photograph, and to the letters and figures of reference marked thereon, which form a part of this specification.

15 The accompanying photograph fully illustrates my design, in which A indicates the fire-place frame, the side uprights, *a a*, of which are each ornamented by relief representations of oak branches, and *b* is an open-work 20 frieze, the solid portions of which are representations of oak branches, leaves, and acorns.

The configuration of the grate C is such that a series of vertical open spaces at the center are flanked on either side by horizontal open 25 spaces, these vertical and horizontal spaces being bounded by the bars *c c' c''* and *c'*, the grate 30 being represented as springing from the side uprights at its ends and bowed outward between them. Below the grate is the fender D, having a central panel, *d*, ornamented with oak branches in relief, while on each side of this central panel is a row of pilasters standing between the base *e* and top bar, *e'*, of the

fender. At each end of the fender is a post, *f*, considerably taller than the main body of 35 the fender, and against these posts abut scroll-pieces *g*, which appear also to rest upon the top bar of the fender.

I claim—

1. The herein described and shown design 40 for a fire-place front, consisting of the side uprights ornamented by oak branches, the open-work frieze of oak branches, the grate having the central series of vertical bars with horizontal bars at the sides thereof, and the fender 45 having the central panel ornamented by oak branches in relief, and having at each side thereof a series of pilasters.

2. In a design for a fire-place front, the side uprights ornamented by oak branches, and the 50 open-work frieze of oak branches at the tops of and between said side uprights, as shown.

3. In a design for a fire-place front, the fender having a central panel ornamented by oak 55 branches in relief, and having at each end a post higher than the main body of the fender, with ornamental scrolls in the angles formed by the posts with the top bar of the said fender, as shown.

In testimony whereof I affix my signature in 60 presence of two witnesses.

EDWIN A. JACKSON.
